OLDS & LOWE, P.C.(57) **CLAIM**

The ornamental design for a breath detecting mat, as shown and described.

DESCRIPTION

FIG. 1 is a top-front perspective view of a breath detecting mat showing our new design;

FIG. 2 is a bottom-front perspective view thereof;

FIG. 3 is an enlarged view of the portion in FIG. 1;

FIG. 4 is a front elevational view thereof;

FIG. 5 is a top plan view thereof; and,

FIG. 6 is a bottom plan view thereof.

The broken lines depict portions of the breath detecting mat that form no part of the claimed design.

The rear, left side, and right side views are the same as the front view.
